UNITED STATES PATENT OFFICE

124,212

DESIGN FOR A SIGN OR SIMILAR ARTICLE

José Trojan, Chicago, Ill., assignor to Owen Householder and David C. Cohen, copartners doing business as Crystal Manufacturing Co., Chicago, Ill.

Application October 25, 1940, Serial No. 96,072

Term of patent 7 years

To all whom it may concern:

Be it known that I, José Trojan, a citizen of the United States, residing at Chicago, in the county of Cook and State of Illinois, have invented a new, original, and ornamental Design for a Sign or Similar Article, of which the following is a specification, reference being had to the accompanying drawing, forming part thereof.

I claim:

The ornamental design for a sign or similar article, substantially as shown.

JOSÉ TROJAN.
